CLAIM

The ornamental design for a christmas tree light, as shown and described.

DESCRIPTION

FIG. 1 is a top, front and right side perspective view of a christmas tree light showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is an enlarged view of portion 8 in FIG. 1;
FIG. 9 is an enlarged view of portion 9 in FIG. 1;
FIG. 10 is an enlarged view of portion 10 in FIG. 1; and,
FIG. 11 is an enlarged view of portion 11 in FIG. 1.
The dash-dot-dash broken lines define the boundary of enlarged views and form no part of the claimed design.
